US00D646381S

(12) **United States Design Patent**
Casini et al.

(10) **Patent No.:** US D646,381 S
(45) **Date of Patent:** ** Oct. 4, 2011

(54) **PRINTED ABSORBENT PAD**

(75) Inventors: **Luca Casini**, Milan (IT); **Franz Aschenbrenner**, Kastl (DE); **Clarice Marie Theisen**, Alpharetta, GA (US); **Maria de las Mercedes Bazterrica**, Atlanta, GA (US)

(73) Assignee: **Kimberly-Clark Worldwide, Inc.**, Neenah, WI (US)

(**) Term: **14 Years**

(21) Appl. No.: **29/312,409**

(22) Filed: **Oct. 17, 2008**

(51) LOC (9) Cl. 24-04

(52) U.S. Cl. **D24/124**

(58) **Field of Classification Search** D24/124-126; 604/358, 383, 384, 385.1, 386, 387, 389, 604/390, 378, 370; D5/53, 56, 57, 58, 60-62

See application file for complete search history.

(57) **CLAIM**

We claim the ornamental design for a printed absorbent pad, as shown and described.

DESCRIPTION

The sole FIGURE illustrates a top plan view of a printed absorbent pad, according to the present invention. The broken lines shown in the drawings are for illustrative purposes only and form no part of the claimed design. The surfaces or portions not shown in the drawings or described in the specification form no part of the claimed design.
